(57) **CLAIM**

The ornamental design for an earring, as shown and described.

DESCRIPTION

FIG. 1 is a perspective view of an earring illustrating my new design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a top plan view thereof; and,

FIG. 7 is a bottom view thereof.

The broken line showing of earring structure in the drawings represents unclaimed portions of the design and forms no part thereof. The broken line showing of an ear represents environmental matter and forms no part of the claimed design.
